UNITED STATES PATENT OFFICE.

HAROLD ROWNTREE, OF KENILWORTH, ILLINOIS, ASSIGNOR TO NATIONAL PNEUMATIC COMPANY, OF NEW YORK, N. Y., A CORPORATION OF WEST VIRGINIA.

TRAIN-SIGNALING SYSTEM.

Original application filed August 3, 1917, Serial No. 184,211. Patent No. 1,347,523, dated July 27, 1920.
Divided and this application filed March 25, 1918. Serial No. 224,417.

To all whom it may concern:

Be it known that I, HAROLD ROWNTREE, a citizen of the United States, residing at Kenilworth, county of Cook, State of Illinois, have made a certain new and useful Invention in Train-Signaling Systems, of which the following is a specification.

This invention relates to train signaling systems and is directed to subject matter 10 divided from my co-pending application Serial No. 184,211, filed August 3, 1917, and patented July 27, 1920, as No. 1,347,523.

The object of the invention is to provide a train signaling system which will insure 15 speed and efficiency of the conductors or guards controlling the doors for the exit and entrance of passengers.

A further object of the invention is to provide a signaling system which I will 20 term a "hurry-up signal" to guards or conductors who are dilatory in closing their doors to allow the forward travel of the car or train.

Further objects of the invention will appear more fully hereinafter.

The invention consists substantially in the construction, combination, location and relative arrangement of parts, all as will be more fully hereinafter set forth as shown 30 by the accompanying drawing and finally pointed out in the appended claims.

Fig. 1 is a diagrammatic wiring diagram showing one portion of a train control and signaling mechanism employed in accordance with my invention.

Fig. 2 is a similar view showing the control and signaling mechanism located on the car structure.

Fig. 3 is a view showing my invention 40 applied to cars in a train.

The same part is designated by the same reference numeral wherever it occurs throughout the several views.

It is among the purposes of my present 45 invention to provide means in a car or a train of cars for giving a hurry-up signal to the guards who are slow in closing their doors after the entrance or exit of passengers. It is well known in the present art, 50 for example, a train of cars, to provide means in the motorman's station in the form of a signal to indicate to him when all of the doors of the train have been closed so

that he may know that he may proceed with his train without waiting for the usual hand signal relayed from car to car of the train. I have shown and will now describe my invention as applied to a train of cars wherein the control thereof is effected at a single station, but I wish it to be understood that 55 my invention in its broader scope and as defined by the claims is equally applicable to single cars or car units where a plurality of doors are to be operated. When all of the cars except a few have their doors closed, 60 in accordance with my invention a hurry-up signal is given on those cars with a door still open in order to hasten the action of the guard, and I provide means for automatically stopping the hurry-up signal the 65 moment the doors on that car are closed. I also provide means in the event that the hurry-up signal continues to operate after the doors are apparently closed, thereby 70 showing that some part of the door signaling system has failed to function, whereby 75 the guard can operate a special switch on the car which will instantly place the safety signaling system of the train in the condition it would occupy if the door switch system on that car had not failed, and thereby causing the hurry-up signal to cease its operation the moment such reserve switch is operated.

I will now describe the mechanism on 80 each car, and in doing this it is not necessary to show or describe the standard mechanism disclosed in my Patents Nos. 1,347,523 and 1,292,077, which mechanism is now in use on cars of individual trains and wherein 85 all cars are controlled from one place, usually at the head of the train. The cars will of course be equipped with the usual motor whereby when a circuit is completed electric control mechanism is put into operation to 90 cause the motor to start and to steadily increase the speed of the motor until the desired maximum speed is attained, and when the electrical connection is broken the electric controlling mechanism is operated to 95 shut off the current from the motor and so bring the motor to rest. The car may be of course equipped with the usual air brakes including compressor, tank, automatic regulator and the suitable electrically controlled 100 valves for controlling the air brake so that 105

when an electrical connection is made the brakes will be liberated and when the electrical connection is broken the brakes will be applied with the maximum pressure consistent with the safety of the equipment and the comfort of the passengers. The mechanism by which this is accomplished is so well known in the art that it is unnecessary to describe it here, and my invention is not to be limited to any details thereof. It is only necessary for me to describe means whereby, at the proper time, the electrical connection is made and broken so that making the electrical connection from the power line liberates the brakes and starts the motor, and breaking the electrical connection will apply the brakes and shut off power from the motor.

In Figs. 2 and 3 I have shown a solenoid 7 which when energized completes the above mentioned electrical circuit, and when de-energized breaks the said electrical circuit. This solenoid 7 is in constant connection with the control circuit and the other terminal of the solenoid 7 is grounded so that current in the control circuit is at all times transmitted to the winding of solenoid 7.

Each door of the car is equipped with a suitable switch as shown diagrammatically at 8, 9 and 10 so connected to the door that the circuit is completed when the door is fully closed and broken when the door is not fully closed. These switches 8, 9 and 10 are in series with each other, one side being connected to the power rail through the power car shoe and the other to one terminal of the winding of solenoid 11, which is grounded as is shown in Figs. 2 and 3. This is a simple arrangement employed where the well known third rail system is employed, and is selected as illustrative of the invention involved. It is obvious, however, that the invention is applicable to any electrically controlled car or train whether it is of the third rail system or not. From the foregoing it will be seen that if all the doors on the car are properly and entirely closed solenoid 11 will be energized, but if any of the doors on that car are open solenoid 11 will not be energized. When solenoid 11 is not energized it makes contact between contacts 12 and 13 but when it is energized this contact is broken. Contact 12 is connected to the control circuit. Contact 13 is connected to one blade of a knife switch as shown at 14. This knife switch is placed in convenient location to the guard on the car for a purpose to be hereinafter described. From the other blade of the switch 14 a connection is made through resistance 16 to the ground and also through an electric sounder 15 to the ground, this sounder, being a bell, buzzer or any other well known form of audible or visible signal, preferably audible.

Before describing how the above mechanism operates, I will describe the controlling mechanism of the train which is diagrammatically shown in Fig. 1. In accordance with the disclosure in my parent application, now Patent No. 1,347,523, this controlling mechanism of the train may be any standard controller, and therefore while I incorporate novel features it is to be understood that my broad invention as defined in the claims is not to be limited to the specific construction diagrammatically shown in Fig. 1 and which I will now describe. The controlling mechanism includes a control handle 46 operating about a pivot 47. This handle carries a contact piece 48 which makes contact with the contact strip 4, and also makes contact with the three button contacts 1, 2 and 3, being so arranged that it will make contact with contact 3 before it leaves contact 2, or with contact 2 before it leaves contact 3, as indicated on dotted lines. Contact 1 is dead and corresponds to the "off" position of the motor controller. Contacts 2 and 3 are connected together through resistance 5. Contact 3 is connected to the control circuit of the car or train, and segment 4 is connected to a source of current supply. An electrical indicator 6 may be inserted in the circuit at any suitable point as between contact 3 and the usual ground connection to indicate difference of potential in the system. The motor M is further controlled by controller C on the car.

The operation of my novel device may be conveniently described as follows:

Let us suppose that handle 46 is on contact 1. There will then be no current supplied to contact 3, and consequently there will be no current in the control circuit. There being no current in the control circuit solenoid 7 on each car will not be energized and the switch which it controls will be open, the brakes operated by the brake valves controlled by solenoids 20 will be applied and the motor will be shut off on each car, in the manner well understood in the art, and therefore no detailed mechanism to accomplish these results is herein illustrated. If now, the control handle is moved to contact 2, current will pass through segment 4, contact piece 48, contact 2, through resistance 5 to contact 3, and then to the control circuit and also through the indicator 6. There will now be current entering the control circuit through resistance 5 and leaving the control circuit through each of the solenoids 7, and the resistance 5 will be so graduated that the amount of current entering the control circuit will be somewhat below that sufficient to energize the solenoids 7, that is, when all the solenoids 7 are in parallel with each other and connecting the control circuit to ground. This insufficiency of the current to energize any of the sole-

noids 7, as stated above, must exist even if all the doors on the train or car are closed, or when solenoids 11 are energized and no current leaves the control circuit 5 through contacts 12 and 13 by way of switch 14 and resistance 16, or the sounder 15.

If all the doors, or a large number of the doors, of the train are open when handle 46 is moved on to contact 2, then the current 10 passing through resistance 5, in addition to being dissipated in the control circuit through all the solenoids 7, will also be dissipated through resistances 16 and sounders 15 on the cars of which any door is open. 15 These resistances will have a sufficient carrying capacity in proportion to the resistance 5 so that there will be practically no voltage drop in the control system so long as any material number of car doors are open, and 20 therefore so long as any material number of resistances 16 are making connection from the control circuit to the ground. Therefore, if any considerable number of doors be open 25 indicator 6 at the motorman's station or at any control station will indicate practically a zero reading.

As soon, however, as a large majority of the car doors are closed, and therefore the corresponding solenoid energized and the 30 connection from the control circuit to the resistance 16 and the sounder 15 is cut out on such cars, the current entering the control circuit through resistance 5 will begin to build up a pressure in the control circuit. 35 By the time there remain open only a few doors, this pressure will be sufficient to cause the sounder 15 to sound on such cars where the doors are open, thereby notifying the guard on each car on which such sounder is 40 heard that his car is delaying the starting of the train. This will cause such guard to immediately redouble his efforts to get his doors all closed. The moment his sounder ceases due to the energization of solenoid 11, 45 he will know that his car is no longer delaying the train. Should, however, it occur that something has gone wrong with one of the door switches, or with the electrical connections, or with solenoid 11, or even 50 with one of the door operating engines, or its control (it being naturally assumed that each door will be a power-operated door controlled by the guard), and the guard finds that he is unable by manipulating the 55 door control to cause the sounder to cease sounding, then by opening the manual switch 14 he will disconnect the control circuit from the resistance 16 and the sounder 15, the same as though this disconnection had 60 been made through the normal operation of solenoid 11, and the train or car will be no longer delayed. In this way, therefore, I prevent the train or car from being unduly delayed, either by the guard being dilatory 65 or by the mechanism on the car becoming

temporarily out of order. The train will thus never be long and will proceed on schedule time.

The indicator which at all times indicates the potential drop in the control circuit 70 will show the constant increase as the number of cars on which any door is open is being reduced; or, where a single car is employed, as the number of open doors on the car is reduced. In the first instance, as the last car has its doors closed, or its switch 75 14 open, which produces the same effect, and the control circuit is freed from any connection to the ground other than through solenoids 7, the indicator 6 will constantly 80 communicate this fact to the motorman and he will instantly move the control handle 46 to contact 3, thereby turn on full current so as to energize all of the solenoids 7, and thus complete the circuit on each car to 85 thereby liberate the brake and start the motor mechanism into action.

When the motorman desires to stop he will move the handle to the dead contact 1, or the off position. Thereupon solenoids 7 will 90 be deenergized, the motor control will be disconnected, the brakes applied and the train will stop. As soon as the train has stopped the motorman will move his control handle 46 to contact 2 so as to obtain through 95 the indicator 6 an accurate indication of when the doors are closed, and his train is permitted to proceed.

It will be seen, therefore, that I have devised an exceedingly simple and efficient arrangement whereby a car, or train of cars, may be controlled so that the car or train can be operated rapidly. By this arrangement the motorman knows when all the doors of the train are closed and when the hurry-up signal is given on the cars that are last to have their doors closed. Moreover, means are provided whereby the guard of any car is enabled to place the system in condition 100 so that the train can be operated even though 105 any part of the safety arrangement on his car has become damaged.

It is obvious that very many different arrangements of car signaling systems may be adopted without departing from the spirit or scope of my invention as defined by the claims. Therefore, what I claim as new and useful, of my own invention, and desire to secure by Letters Patent, is:-

1. In a train of cars and in combination with the doors thereof, of signal devices on each car, and means controlled by the closing of a predetermined number of doors for operating the signal devices on the cars, the doors of which remain open.

2. In a train of cars and in combination with the doors thereof, of signal devices on each car, and means including switches controlled by the opening and closing of the doors for operating the signal devices on

the cars the doors of which remain open when a predetermined number of doors have been closed.

3. In a train of cars, the combination with doors for the cars and a signal device in each car, of means controlled by the closing of the majority of the doors of the train for operating the signal devices on the cars, the doors of which remain unclosed, and 10 manually operated means located on each car for rendering the signal device thereof inoperative independent of the door controlled means.

4. In a train of cars and in combination 15 with the doors on said cars, of a signal device for each car, and means influenced by the closing of the majority of the doors of the train for rendering operative said signal device on the cars the doors of which remain unclosed.

5. In a train, the combination with doors of hurry-up signals for said doors, means controlled by the closing of most of the doors of the train for rendering operative the hurry-up signals of the doors remaining 25 open, and means for rendering the signals inoperative independent of the door controlled means.

6. In a train, the combination with door switches for doors on said train, signals for 30 said doors, and means including said switches influenced by the closing of the majority of the doors of the train for operating the signals of the doors remaining open. 35

In testimony whereof I have hereunto set my hand on this 21st day of March A. D. 1918.

HAROLD ROWNTREE.
